UNITED STATES PATENT OFFICE.

EDWARD O'HANLON, OF DAVENPORT, IOWA.

PROPELLER.

1,281,642.

Specification of Letters Patent. Patented Oct. 15, 1918.

Application filed January 7, 1918. Serial No. 210,709.

To all whom it may concern:

Be it known that I, EDWARD O'HANLON, a citizen of the United States, and resident of Davenport, in the county of Scott and State 5 of Iowa, have invented a new and useful Propeller, of which the following is a specification.

The present invention relates to propellers for boats, and relates more particularly to a 10 propeller of the reciprocating type.

The object of this invention is to provide a propeller which comprises a relatively simple and compact structure embodying few parts which admit of strength in their 15 formation and which may be readily assembled; a propeller which may be easily reciprocated by hand; a propeller which is provided with an automatically adjustable blade adapted to be swung into an operative 20 position for offering resistance to the impact of water thereagainst not only by virtue of the mounting of the blade, but also by an inherent buoyancy tending to raise the blade; and to provide a propeller with a blade and 25 mechanical actuating means for urging the same into a position to offer resistance to the water upon the impact stroke of the propeller.

The above, and various other advantages 30 and objects of this invention will be in part described and in part understood from the following detailed description of the present preferred embodiment, the same being illustrated in the accompanying drawing, 35 wherein:

Figure 1 is a side elevation of a boat having a propeller constructed according to the present invention applied thereto.

Fig. 2 is a detail front elevation of the propeller, enlarged, the same being in position 40 to offer resistance to the fluid medium.

Fig. 3 is a longitudinal section taken through the same substantially on the plane indicated by the line 3-3 in Fig. 2.

Fig. 4 is a similar view showing the blade 45 in lowered position for decreasing the impact of the propeller upon its idle stroke.

Fig. 5 is a detail fragmentary elevation of the upper end of the propeller, showing one 50 manner of mounting the same.

Fig. 6 is a longitudinal section taken substantially on the line 6-6 of Fig. 5, showing a modified form of tension means for urging the blade into operative position.

55 Referring to this drawing A designates a boat or water craft of any suitable construc-

tion, and which is provided with a longitudinal upstanding frame 10 including side bars 11 arranged at opposite sides of the frame and above the hull of the boat A. 60

The propeller comprises an arm 12 to the outer or lower end of which is hingedly connected a blade 13. The arm 12 is in the form of a relatively long lever turned laterally at its upper end to form a journal 14 65 secured in a hanger bearing 15 which is carried upon a beam 11. Intermediate the ends of the arm 12, the latter has a handle 16 adapted to be grasped by the hand for swinging the arm 12 upon its upper pivoted 70 end as a center to oscillate the blade 13.

A T-head 17 is carried upon the lower end of the arm 12 and provided with a transverse bolt or trunnions 18 adapted to pass through eyes 19 outstanding in spaced relation from 75 the upper or forward side of the blade 13. Nuts 20 or the like are secured on the opposite ends of the trunnions 18 for retaining the blade 13 upon the lower end of the arm 12. The blade 13 is adapted to swing down 80 at substantially right angles to the longitudinal axis of the arm 12, as shown in Fig. 4, to reduce the resistance of the propeller in traveling through the water during the 85 idle stroke, or during the movement of the propeller into a position to obtain a purchase upon the fluid medium.

The blade 13 is relatively wide and long and is provided in its upper or forward 90 face with a relatively deep concavity extending throughout the major portion of the blade and into which a body of cork 21 or other suitable buoyant material is placed for the purpose of normally urging the 95 blade 13 to swing up into operative position.

To augment the action of the buoyant material 21, a spring 22 may be interposed between an arm 23 on the lower end of the arm 12 and a connection or arm 24 on the forward end of the blade 13, the arm 24 being curved upwardly from the blade and adapted to register beneath the arm 23 when the blade is lowered. The spring 22 is secured at opposite ends to the arms 23 and 24 100 and is adapted to normally urge the arm 24 down and raise the blade 13 against the rear side of the arm 12.

The modification shown in Figs. 5 and 6 shows a downwardly flaring socket 25 in 110 the form of a sleeve through which slidably engages a rod 26 provided on its upper end

with a weight 27 and a foot 28 upon its lower end adapted to bear against the upper face of the blade 13 forwardly of the pivot 18 to urge the rear end of the blade upward. The socket 25 is flared downward to admit the oscillation of the rod 26 as the foot 28 rocks upon the forward end of the blade as the latter swings up and down.

In operation, the arm 12 is swung forward 10 at its lower end and the resistance of the fluid medium against the blade 13 swings the latter down into a horizontal position to reduce the resistance of the propeller to forward movement.

15 As soon as the propeller reaches the end of its forward stroke, the buoyancy of the propeller together with the lifting means, such as the spring 22 or the weight 27, urges the blade to immediately rise against the 20 rear side of the arm 12, the latter serving as a brace to support the blade and relieve the hinge 18 thereof from the greater portion of the strain. The eyes 19 are spaced apart upon the blade to effectively hold it 25 from swaying or bending laterally. The lower end of the arm 12 is now drawn back and the resistance of the relatively large surface area of the blade 13 is brought into 30 full contact with the fluid medium to offer considerable resistance to movement and thus transmit a counter force through the arm 12 to the frame 10 and the craft A.

It is of course understood that various changes and modifications may be made in 35 the details of construction and design of the above specifically described embodiment of this invention without departing from the spirit thereof, such changes and modifications being restricted only by the scope of 40 the following claims.

What is claimed is:

1. In a propeller, the combination with a boat, of a frame rigidly attached to the boat and rising therefrom, a pair of arms 45 having their upper ends bent inwardly and pivotally connected to said frame, handles

attached to and extending inwardly from said arms intermediate their ends, blades pivotally connected to the lower ends of said arms to form a transverse pivot and 50 adapted to swing against the rear side of the arms upon the impact stroke of the propeller and further adapted to swing down into a substantially horizontal position upon the forward stroke of the propeller, and 55 means for assisting in urging said blades against the rear sides of the arms upon the impact stroke of the propeller.

2. In a propeller, the combination, with a boat, of a frame rigidly attached to the boat 60 and rising therefrom, an arm having its upper end pivotally connected to the frame, a blade pivotally connected to the lower end of said arm, an arcuate plate carried by said blade and curving over its pivot, brackets 65 carried by said arm, and an expansion spiral spring positioned between said brackets and arm for assisting in urging said blade against the rear side of the arm upon the impact stroke of the propeller. 70

3. In a propeller, the combination with a boat, of a frame rigidly attached to the boat and rising therefrom, a pair of arms having their upper ends bent inwardly and pivotally connected to said frame, handles attached to and extending inwardly from said arms intermediate their ends, blades pivotally connected to the lower ends of said arms to form a transverse pivot and adapted to swing against the rear side of the 80 arms upon the impact stroke of the propeller and adapted to swing down into a substantially horizontal position upon the forward stroke of the propeller, arcuate plates carried by said blades and curving over 85 their pivots, brackets carried by said arms, and expansion spiral springs positioned between said brackets and arms for assisting in urging said blades against the rear sides of the arms upon the impact stroke of the 90 propeller. 75

EDWARD O'HANLON.
